METHOD AND APPARATUS FOR INSTALLING
FASTENERSOtto J. Huelster, Waterbury, Conn., assignor to
Scovill Manufacturing Company, Waterbury,
Conn., a corporation of Connecticut

Application June 12, 1942, Serial No. 446,838

17 Claims. (Cl. 218—5)

This invention relates to snap-fastener installations, and is more particularly concerned with a method of and tools for forming snap-fastener members of the type disclosed in a copending application of the same inventor, filed March 30, 1942, Serial No. 436,728, now Patent Number 2,328,016, granted Aug. 31, 1943.

The principal object of the invention is to provide a method of completing the formation of the component members of a snap-fastener installation by applying to them means which will allow the socket member to be separated from its cooperating stud only in response to a pull applied to the fastened members at one particular place on their peripheries, which method is adapted to be carried out either during the course of attaching the members to their supporting sheets, or after they have been secured in place, whereby to avoid any need for orienting the members preliminary to their attachment and yet produce a completed installation in which the one-way limiting means lie in a predetermined and definite relation to the sheets.

A more specific object of the invention is to provide a method of forming a lip in the mouth of an otherwise completed snap-fastener socket member, which lip is of such a nature as to permit the socket to be separated from a cooperating stud only in response to a pull applied immediately over and under it; and tools which are adapted to rivet or otherwise secure the socket to a supporting sheet while simultaneously forming a one-way limiting lip on the socket at a definite point with respect to the sheet in accordance with the method.

It is another specific object of the invention to provide a method of deforming the head portion of a snap-fastener stud member from its conventional, truly circular conformation in such a way as to facilitate separation of the stud from a one-way limiting socket; and tools for carrying out this method while simultaneously attaching the stud to its supporting sheet whereby the deformed portion of the stud may bear a desired relation to its supporting sheet in the completed installation.

The foregoing and other objects of the invention, as well as various features thereof, will be more fully understood from a consideration of the following description and accompanying drawings, in which—

Figure 1 is a plan view of a partly completed socket of the kind with which the invention deals;

Fig. 2 is a sectional view of the partly completed socket of Fig. 1 and of an attaching rivet, dis-

posed on opposite sides of a supporting sheet and in cooperative relation with a pair of tools constructed in accordance with the invention, this view illustrating the positions of the several parts at the start of the forming and attaching method;

Fig. 3 is a sectional view, similar to Fig. 2, illustrating the positions of the fastener parts and setting tools at an intermediate stage of the method of the invention;

10 Fig. 4 is a sectional view illustrating the final stage of the method, this view being taken on the line 4—4 of Fig. 3 in order to illustrate certain details of the tools which cannot be seen in that figure;

15 Fig. 5 is a plan view of a conventional snap-fastener stud member which is to be completed in accordance with the invention;

20 Fig. 6 is a sectional view of the stud member of Fig. 5 and an attaching rivet therefor, the parts being disposed on opposite sides of a supporting sheet and in cooperative relation with a pair of forming and setting tools constructed in accordance with the invention, and adapted to carry out the method;

25 Fig. 7 is a plan view of a portion of the upper one of the setting tools of Fig. 6;

30 Fig. 8 is a sectional view, similar to Fig. 6, illustrating the bringing together of the tools to secure the stud member to its supporting sheet, while simultaneously completing the formation of the stud pursuant to the method of the invention, the section of this figure being taken on the line 8—8 of Fig. 6; and

35 Fig. 9 is an elevational view of the conventional stud member of Fig. 5, with certain parts broken away better to show underlying ones.

In the drawings, and referring to Figs. 1 and 2, numeral 10 identifies generally a partly completed snap-fastener socket member of which the body is a shell which has been stamped and drawn from a sheet-metal blank to provide it with a crown portion 11 having a central opening 12 for receiving the end of a tubular attaching rivet, a back flange 15 extending more or less abruptly 40 outward from the margin of the crown, and a peripheral wall 16 extending forwardly and inwardly from the back flange, these various elements forming collectively a recess 17 of tapering proportions, having its largest diameter adjacent the back flange and its smallest diameter at the mouth 18. The spring element of the assembly is preferably a simple split spring ring 20, which is of such size that it may be expanded, when forced against the back flange by a cooperating snap-fastener stud member, to permit

the head of that stud to pass through it and into the crown 11, in the usual way, and yet when drawn against the tapered wall 16 will be contracted around the neck of the stud member to hold it in fastened relation in the socket.

The socket has been called "partially completed" because it has not yet been provided with the one-way limiting lip 21 (shown in dotted lines in Fig. 1) which allows the member to be released from an engaged stud. The operation, briefly, is this: When a pull is applied immediately above and below the lip, the fastened socket and stud move to such relative positions that the axially tiltable portion of the ring 20 then lies in the enlarged rear end of the stud-receiving recess 17 adjacent the back flange 15 where there is plenty of room for it to expand to release the head of the stud. A pull upon the fastened members at any other point, however, will draw the tapered wall 16 against the axially tiltable portion of the ring 20 to confine that element and prevent its expansion, thereby preventing the release of the socket from the stud. A fuller understanding of the constructional details of the socket member and the manner in which it operates, may be had by reference to the above-identified pending application.

It will be evident that the completed socket must be installed with its one-way limiting lip 21 lying in a desired and predetermined relation to a supporting sheet so that the point of application of the separating pull to that sheet will always be determinate. In accordance with the method of the invention this is accomplished by first affixing the partly completed member to a supporting sheet, and by then upsetting its mouth 18 to form the required one-way limiting lip. Since the partly completed socket is of substantially circular cross section, it has no positional qualities and may be placed at a desired point upon the sheet without any other preliminary orientation; and the lip 21 may then be formed at a desired point to produce a finished socket in which the one-way limiting means bears a proper relation to the sheet. It is preferred that this method be carried out as a part of the operation wherein the socket is installed upon its supporting sheet, in which case it comprises the steps of placing an incomplete member and an attaching rivet on opposite sides of the sheet in back-to-back relation; of then forcing the member and rivet together whereby to lock a part of one with a part of the other, with the sheet material firmly engaged between their opposing surfaces; and of simultaneously bending the mouth 18 of the shell of the socket inwardly to form the lip 21 at what may be called an oriented position with respect to the sheet.

The method may be better understood by considering the carrying out of its essential steps in a fastener-attaching machine equipped with tools constructed in accordance with the invention as illustrated in Figs. 2 to 4, inclusive. The details of the machine, as distinguished from the tools, form no part of the invention, and have not been illustrated. In order to simplify the description it will be assumed that the machine is of the type in which its plunger 22 reciprocates the setting tool 23 towards and away from the relatively stationary anvil tool 24; and that the machine is not complicated by the provision of automatic feed mechanism. At the start of the operation, therefore, when the tools are most widely separated, a partly completed socket member 10 is placed by hand over the end of the central part 25 of

the setting tool 23, and is pressed upwardly until the mouth 18 of its shell is brought to rest against the flange 27 of the sleeve 28, which is slidably mounted upon the central part and is urged downwardly to its normal position by a spring 29. It will be noted that the relative dimensions of the sleeve and central part are such that, in applying the member as just described, its back flange 15 will engage spring ring 20 and expand that element over the slightly larger lower end of part 25. Accordingly, when the shell of the socket is released, it drops to the position shown in Fig. 2, where it is held by the resilient engagement of the ring with the tool. In this position, however, the lower end 30 of the sleeve still lies partially within the shell whereby to hold that element in a centered position during subsequent operations. As a further preliminary, an attaching rivet 31 is placed upon the shaped face of the anvil 24 with its cap portion 32 firmly supported and with its central tubular barrel 33 aligned with the opening 12 in the shell of the socket. The socket and rivet having been arranged in back-to-back relation, that part of the supporting sheet 34 on which the installation is to be made is interposed between the crown of the shell and the end of the tubular portion of the rivet.

Upon the completion of these preliminaries the machine may be started to cause its plunger 22 to descend, carrying with it the associated setting tool 23. In the first portion of this movement the setting tool places the socket upon the supporting sheet, and the flange 27 of sleeve 28 then engages the mouth of the shell to press that element firmly against the flexible supporting material, while the lower end 30 of the sleeve guides the shell and holds it in a centered position, as illustrated in Fig. 3. Further downward movement forces the socket and rivet together, causing the end of the barrel 33 of the latter part to pierce the sheet and to enter the socket through the opening 12 in its crown. As the tool approaches the lowermost extremity of its movement, its sleeve 28 is brought to rest against the reaction of supporting spring 29 whereby to hold the socket firmly in its established position. The central part 25, however, continues to move, so that its setting surface 35 may engage the end of the rivet and turn that part outwardly, while its surrounding surface 36 presses the crown of the socket firmly against the sheet. The socket is thus securely attached to the sheet material, with the tines 37 on its back flange and the similar tines 38 on the rivet digging into the material deeply enough to prevent rotary movement of either part with respect to the sheet in subsequent use of the fastener. Simultaneously with the setting action, a notching pin 39, which is carried by the central part 25 with one of its ends projecting laterally through a slot 40 in the surrounding sleeve at a fixed distance above the setting surface 35, engages the mouth 18 of the shell and bends the adjacent part of the tapered wall 16 inwardly to form the one-way limiting lip 21. In this operation, of course, the major part of the mouth of the shell is supported by the flange 27 and the end portion 30 of the sleeve 28, so that the bending action may be a clean and satisfactory one. It will also be apparent that the notching pin 39 serves a further function in limiting downward movement of the sleeve 28 upon the central part in response to the urging of its spring 29—it defines the normal elevated position of the sleeve with respect to the central part.

Since the notching pin is located in a fixed

angular relation to the central part of the tool, and since that tool itself is held against rotative movement in the plunger, as, for example, by a set-screw 41, it is apparent that the lip 21 will always be formed upon the shell of the socket at a predetermined point. Accordingly, if the sheet material 34 is interposed between the tools at the start of the operation, in a desired position with respect to the notching pin, the lip 21 must appear in the completed and installed member in an oriented relation to the sheet.

The final stage of the attaching and lip-forming method is illustrated in Fig. 4. Thereafter the plunger 22 and the upper setting tool 23 may be retracted in the normal operation of the machine to the positions shown in Fig. 2, at which time the sheet 34 may be withdrawn with the now completed one-way detachable socket member secured to its surface.

The socket which has been described above may be used in conjunction with a stud member 42 of conventional design (Fig. 9) comprising, for example, a base flange 43 having a central post with a contracted neck 44 adjacent its truly circular head 45 (as shown in full lines in Fig. 5), and a central opening 46 for receiving the end of an attaching rivet by which the member is secured to a supporting sheet. If an easier separation of the fastened members is desired, that is to say, a softer acting snap fastener is wanted, it can readily be gotten by using a stud of special character having its head 45 flattened or relieved to a very slight extent, as indicated at 47 in dotted lines in Fig. 5, at each side of that one of its sectors which will underlie the lip 21 of the socket when the members are fastened together in their normal positions. In accordance with the invention this special form of stud may be made from one of conventional design by bending a portion of its head outwardly in such a way as to draw the adjacent portions of that head inwardly to form the relieved sectors 47. Here, again, the method is adapted to be practiced as a part of the operation wherein the stud member is secured to a supporting sheet. Briefly stated, this combined method comprises the steps of disposing a stud of conventional design (which may be called a "partly completed member") and an attaching rivet 48 in back-to-back relation on opposite sides of a supporting sheet 49, of then forcing the member and rivet together whereby to interlock a part of one with a part of the other, with the sheet material clamped between them, and of simultaneously supporting laterally all portions of the head except those which are to constitute the relieved sectors, while bending outwardly substantially the mid-section of the unsupported portion of the head. Accordingly, when the mid-portion 50 is pushed laterally outward, the immediately adjacent and unsupported portions will be drawn inwardly to form the relieved sectors 47 in question.

The method, as applied to the completion of a stud member, may be more fully understood by considering its practice in a fastener-setting machine which is equipped with tools constructed in accordance with the invention as illustrated in Figs. 6, 7 and 8. Here, again, the details of the machine and its auxiliary equipment, as distinguished from the tools, form no part of the invention, and have not been illustrated. For ease of description it will be assumed that the machine is of such character as to reciprocate the setting tool 51 towards and away from the anvil tool 52; and that the fastener parts are fed to it

by hand rather than by automatic equipment. At the inception of the method, therefore, when the tools are most widely separated, a partly completed stud member 42 is inserted into the open end of sleeve 53 which surrounds the central part 54 of the setting tool, and is forced upwardly until its head 45 expands the spring ring 55 carried by the sleeve, and allows that ring to enter the contracted neck 44 of the member. The spring thus serves to hold the member within the sleeve as shown in Fig. 6. At this time, also, an attaching rivet 48 is placed upon the anvil portion 56 of the lower tool within the recess defined by the sleeve element 57. When the members have been thus disposed in back-to-back relation, that part of the supporting sheet upon which the installation is to be made is inserted between the aligned opening 46 in the stud and the end of the barrel 58 of the rivet.

Upon the completion of these preliminaries the machine may be started to cause the upper tool 51 to descend towards the anvil tool 52. In this operation the sleeve 53 serves first to place the stud upon the top surface of the supporting sheet, and then to press that sheet between the under surface of the central part of the stud and the open end of the barrel 58 of the rivet. Continued downward movement will, of course, cause the end of the rivet to pierce the sheet and to enter the opening 46 in the stud. Thereafter the head 60 of sleeve 57 engages the underside of the sheet against the underside of the flange 43 of the stud; and the sleeve begins to recede against the reaction of its supporting spring 61 to expose more of the barrel of the rivet and allow that part to penetrate farther into the stud. As the upper tool approaches the lowermost extremity of its movement, the lower sleeve will be brought to rest by the engagement of the ends of its slots 62 with the ends of the cross-pin 63. This necessarily places a limit upon further movement of the upper sleeve 53, and causes the shaped end of the upper tool to enter the open well of the stud, thereby bringing its setting surface 64 against the end of the barrel of the rivet to turn that element outwardly and clinch the stud to the sheet. Simultaneously with this action the tapered buttressing surface 65 of the tool will be brought into engagement with the complementally tapered surface of the well portion of the stud to buttress the major portion of it; and the bending surface 66 of the tool, which is tapered more abruptly than the buttressing surface 65, will be brought into progressive engagement with the section 50 of the head of the stud. In between these two surfaces 65, 66, the tool is recessed as indicated at 67, thus leaving the immediately overlying portions of the stud head unbuttressed. Accordingly, as the tool approaches the lowermost extremity of its movement, the more abruptly tapered surface 66 forces the turned-over rim of the mid-section 50 of the stud head out of its truly round contour; and in this action the adjacent unbuttressed sectors of the head, which lie over the recessed portions 67 of the tool, will be drawn inwardly to form the relieved sectors 47, as shown in dotted lines in Fig. 5. The operation is then complete, and the tools may be retracted to their initial positions, as shown in Fig. 6; after which the sheet 49 may be withdrawn with the stud securely attached to its surface and completed by the deformation of its head to the shape shown in dotted lines in Fig. 5.

The method of completing the formation of the socket and stud members of a snap-fastener installation has been described as being carried out during the operation wherein the members are attached to their supporting sheets, and the tools shown are adapted both to set the members and to complete their formation in a single operation. It will be evident, however, that the method may be carried out to complete the members subsequent to their installation. Thus, if desired, the socket 10 may be secured to a sheet 34 in any conventional way, and a portion of its wall 16 may then be upset by a tool having a notching pin, such as 39, to provide it with a one-way limiting lip 21 located in an appropriate position with respect to the sheet. It is likewise entirely practicable to secure the stud member to its supporting sheet 49 in any conventional fashion, and then to deform its head by subjecting it to the action of a tool having a surface which will buttress laterally a large part of the head, another surface which is adapted to bend outwardly the part of the head of the stud which it engages, and relieved portions at each side of the bending surface which allow the parts of the stud head overlying them to be drawn inwardly in the manner already described.

It will be observed that in each of the described instances the method is practiced upon a snap-fastener member having a wall portion which is of substantially circular cross section; that the member is completed by buttressing laterally a major portion of that wall while bending the unbuttressed portion thereof; and that the bending is directed inwardly. Thus, in completing the socket member 10 of Fig. 1, its initially circular wall 16 is supported laterally along the major portion of its mouth 18, leaving unbuttressed only a small sector which lies in a desired relation to the sheet, and that sector is then bent inwardly and rearwardly of the member to form the one-way limiting lip 21. Similarly, in completing the stud member 42 of Figs. 5 and 9, the major portion of the wall or walls which define its initially circular head is buttressed laterally, leaving unbuttressed those sectors 47 which lie in a desired relation to the sheet; and the mid-section 50 of the unbuttressed part is then forced outwardly whereby to draw inwardly the adjacent sectors 47.

The method has been described in connection with its practice upon a single form of socket, and one type of stud, by specific forms of tools incorporated as parts of a standard setting machine in which the upper tool is reciprocated towards and away from the lower one. It will be apparent to those familiar with the art, however, that various forms of one-way limiting fastener members embodying the inventions of the identified pending application may be completed by the method of the present invention, that other tools embodying the features of the invention may be devised by the mechanic skilled in the art to meet the needs of particular cases, and that these tools may be incorporated in any appropriate type of setting machine, or that the tools may be actuated by hand if that is desired. Accordingly, since the invention is capable of practice in various ways upon fastener members of different designs, and since the illustrated tools are capable of modification without departing from the invention, it is intended that

the foregoing shall be construed in a descriptive rather than in a limiting sense.

What I claim is:

- 5 1. The method of completing the formation of a one-way detachable snap fastener member which is adapted to be secured to a supporting sheet and has an annular wall, a part of which is deformed out of annular contour thereof, said method comprising the steps of securing a snap fastener member having an annular wall upon a supporting sheet, and of then deforming that portion of its annular wall which lies in a desired relation to the sheet in such a way as to complete the member and render the fastener restrictive in its detachable relation with a complementary fastener member.
- 10 2. The method of completing the formation of a one-way detachable snap fastener member which is adapted to be secured to a supporting sheet and has an annular wall prior to completion of the member, said method comprising the steps of substantially simultaneously securing said member at a desired place upon a supporting sheet and of deforming its annular wall inwardly at a predetermined point with respect to the sheet to facilitate its separation from an engaged cooperating fastening member only in response to a pull applied immediately above and below said deformed portion of the wall.
- 15 3. The method of completing the formation of a one-way detachable snap fastener member from a fastener member of the type having an annular wall, which method is adapted to be carried out as a part of the course of attaching such a member to a supporting sheet by means of an attaching rivet which is adapted to pass through the sheet and to enter and be engaged with a cooperating portion of the member; said method comprising the steps of disposing such a snap fastener member having an annular wall and an attaching rivet in back to back relation on opposite sides of a supporting sheet, of then forcing said member and rivet together to interlock a part of one with a part of the other with the supporting sheet clamped between them, and of substantially simultaneously deforming a portion of the annular wall of said member which lies in a predetermined relation to the sheet whereby to complete the formation of the member and render the fastener restrictive in its detachable relation with a complementary fastener member.
- 20 4. The method of completing the formation of a one-way snap fastener socket member from a socket member of the type having an annular wall which tapers forwardly and inwardly of the member to define a stud-receiving recess, and a split-ring spring element which is of such normal diameter as to be capable of lateral expansion when located in the rear of said recess and to be engaged by said wall to prevent such expansion when confined forwardly in the recess, said method comprising the steps of securing a socket member of the type set forth to a supporting sheet at a desired point and of bending inwardly a limited portion of said annular tapering wall which lies opposite a desired portion of the sheet to form means on said wall which will serve to pivotally confine a portion of the spring ring of the member within the enlarged rear end of its stud-receiving recess.
- 25 5. The method of completing the formation of a one-way detachable snap-fastener socket member from a socket member of the type comprising a sheet-metal shell having an annular wall

which tapers forwardly and inwardly to define a recess having a mouth through which a cooperating stud member may be entered, and a split spring ring in said recess, which ring is of such normal diameter that it may expand when located in the enlarged rear end of the recess but will be held against expansion by engagement with said tapered wall when confined forwardly in the recess; said method being carried out in the course of attaching a socket member of the type set forth to a supporting sheet by means of a rivet which is adapted to pass through the sheet and to enter and be engaged with a part of the shell of the socket member, and comprising the steps of: disposing such a member and such a rivet on opposite sides of a supporting sheet in back-to-back relation, forcing the member and rivet together to cause a part of one to interlock with a part of the other with the supporting sheet clamped between them, buttressing annularly the major portion of the open mouth of the shell to prevent its sidewise movement while leaving unbuttressed that portion which lies in a desired positional relation to the supporting sheet, and of simultaneously bending rearwardly and inwardly the unbuttressed portion of the mouth whereby to form a lip on the tapered wall which will pivotally hold a part of the spring ring within the enlarged rear end of the stud-receiving recess of the shell.

6. The method of completing the formation of a one-way detachable snap-fastener stud member from a stud member of the type comprising a sheet-metal post having a contracted neck, and an enlarged head which is of substantially circular cross section prior to completion of the member, said method comprising the steps of buttressing laterally the major portion of the inside of the head of such a stud member while leaving its remaining portions unbuttressed, and of simultaneously deforming laterally outward substantially the mid-section of the unbuttressed portions whereby to draw inwardly the adjacent unbuttressed sectors of the head.

7. The method of completing the formation of a one-way detachable snap-fastener stud member from a stud member of the type comprising a sheet-metal post having a contracted neck, and an enlarged head which is of substantially circular cross section prior to completion of the member, said method comprising the steps of securing such a member to a supporting sheet at a desired place thereon, of then buttressing laterally the major portion of the inside of the head while leaving the remaining portions unbuttressed, and of simultaneously deforming laterally outward substantially the mid-section of said unbuttressed portions whereby to bend inwardly the adjacent unbuttressed sectors.

8. The method of completing the formation of a one-way detachable snap-fastener stud member from a stud member comprising a sheet-metal post having a contracted neck, and an enlarged head which is of substantially circular cross section prior to the completion of the member, which method is carried out in the course of attaching such a stud to its supporting sheet by means of an attaching rivet which is adapted to pass through the sheet material and be engaged with a part of the stud; said method comprising the steps of: disposing such a member and attaching rivet upon opposite sides of a supporting sheet in back-to-back relation, forcing said member and rivet together whereby to interlock a part of one with a part of the other

5 with the sheet material firmly clamped between them, simultaneously buttressing laterally the major portion of the inside of the head of the stud while leaving the remaining portions unbuttressed, and deforming laterally outward substantially the mid-section of the unbuttressed portions whereby to draw inwardly the adjacent unbuttressed sectors of the head.

9. In a machine for completing the formation 10 of a one-way detachable fastener member from a fastener member of the type having a sheet-metal annular wall while simultaneously securing the member to a supporting sheet by means of a rivet; an anvil and a setting tool disposed in aligned relation and movable towards and away from each other, said setting tool comprising a central part, a sleeve slidably mounted on said central part, a spring for urging said sleeve towards said anvil, said sleeve being adapted to 15 maintain a fastener element of the type mentioned in aligned relation with said central part, said central part having its end surface shaped to engage and clinch within the member the end of a rivet supported on said anvil when said tool and anvil are moved towards each other, and means carried by said central part for engaging and bending out of its annular contour a limited portion of the annular wall of the fastener member to complete its formation during the movement 20 of said anvil and tool.

10. In a machine for completing the formation 25 of a one-way detachable fastener member from a fastener member of the type having a substantially annular sheet-metal wall while simultaneously securing the member to a supporting sheet by means of a rivet; a relatively stationary anvil, a setting tool aligned with said anvil and movable towards and away therefrom, said tool comprising a central part which is

30 adapted to be positively moved towards said anvil, a sleeve slidably mounted on and carried by said central part, a spring for urging said sleeve towards said anvil, said sleeve being adapted to maintain a fastener part of the type mentioned in aligned relation with said central part, said central part having its end surface shaped to engage and clinch within the member the end portion of a rivet supported on said anvil when said tool is moved towards said anvil, and means carried by said central part for engaging and bending out of its annular contour a limited portion of the annular wall of the member whereby to complete its formation during the movement of said tool towards said anvil.

35 11. In a machine for simultaneously securing 50 to a supporting sheet and completing the formation of a one-way detachable snap-fastener socket member from a socket member of the type having a substantially annular sheet-metal wall defining a recess with its free edge forming a mouth through which a stud may be entered and a split spring ring confined in such recess; an anvil element and a setting tool disposed in aligned relation and movable endwise towards and away from each other, said tool comprising a central part having an outside diameter slightly exceeding that of the inside normal diameter of the split ring of a fastener member of the type mentioned whereby that ring may be resiliently engaged with the central part to hold the member upon the tool, a sleeve element slidably mounted on said central part, a spring for urging said sleeve to a normal position at which its end lies behind the end of the central part; said sleeve having a flange on its end with a slot therein, which

flange is adapted to enter the mouth of a fastener member and to buttress substantially all of the circular wall thereof except that portion which overlies the mentioned slot, said central part having an end surface which is adapted to engage and clinch within a fastener member disposed thereon the end portion of a rivet supported on said anvil when said tool and anvil are moved towards each other, and a notching pin carried by said central part at a fixed distance above its end surface with one of its ends projecting through the slot in said sleeve, said notching pin being adapted to engage and bend the unbuttressed portion of the annular wall to complete the formation of the member during the movement of said tool and anvil towards each other.

12. In a machine according to claim 11, further characterized in that said notching pin is adapted to engage said sleeve and limit movement of that element under the urging of said spring.

13. In a machine for simultaneously securing to a supporting sheet and completing the formation of a one-way detachable snap-fastener stud member from a stud member of the type having a substantially annular sheet-metal wall defining a head for the member and an open well in its top, and a contracted neck lying below the head: an anvil element and a setting tool disposed in aligned relation and movable endwise towards and away from each other, said tool comprising a central part, a sleeve slidably mounted on said central part, a spring for urging said sleeve to a normal position at which its end lies ahead of the end of said central part, said sleeve being adapted to hold a stud member of the type mentioned and to maintain it in centered relation to said central part, a spring element in said sleeve for engaging the contracted neck of a stud member entered therein and for resiliently holding such member in said sleeve, said central part having its end shaped to engage and clinch within a stud member supported by said sleeve the end of an attaching rivet mounted on said anvil when said anvil and tool are moved towards each other, and other means on the end of said central part for engaging and bending out of its annular contour a part of the annular wall of such a member to complete its formation during the movement of said anvil and tool towards each other.

14. In a machine according to claim 13, further characterized in that said sleeve has a slot extending lengthwise thereof, and by the provision of a pin carried by said central part with an end portion projecting into the slot of said sleeve

whereby to limit movement of the latter element upon said central part under the urging of said spring.

15. In a machine according to claim 13, further characterized in that said means on the end of the central part for engaging and bending a part of the annular wall of a stud member comprises a projecting portion which is adapted to enter the well of a stud member of the kind mentioned supported in said sleeve when said anvil and tool are moved towards each other, said projecting portion having a surface which is adapted to engage and buttress laterally the major portion of the annular wall of the member, and another surface which is adapted to engage and bend another portion of the annular wall to complete the formation of the member.

16. In a machine according to claim 13, further characterized in that said means on the end of the central part for engaging and bending a part of the annular wall of a stud member comprises a projecting portion which is adapted to enter the well of a stud member of the kind mentioned supported in said sleeve when said anvil and tool are moved towards each other, said projecting portion having a surface which is adapted to engage and buttress laterally the major portion of the annular wall of the member, a pair of relieved portions which do not engage nor buttress the wall of the member, and another surface lying between said relieved portions, which surface is adapted to engage and bend outwardly a portion of the wall whereby to draw inwardly the adjacent and unbuttressed portions thereof.

17. In a machine according to claim 13, further characterized in that said means on the end of the central part for engaging and bending a part of the annular wall of a stud member comprises a projecting portion which is adapted to enter the well of a stud member of the kind mentioned supported in said sleeve when said anvil and tool are moved towards each other, said projecting portion having a frusto-conical tapered surface which is adapted to engage and buttress laterally a major portion of the annular wall of the member, a pair of relieved surfaces which neither engage nor buttress the annular wall, and a second frusto-conical surface which is tapered more abruptly than the first-mentioned one, said surface lying between said relieved portions and being adapted to engage and bend outwardly one portion of the annular wall of the member whereby to draw inwardly the sectors of the wall which lie over the relieved sectors.
